[57] ABSTRACT

A butt end stitching machine adapted to carry-out sewing and cutting operations on fabrics and having a one-piece structure within which all machine operating components are arranged. A gun handle is provided in order to grip, direct and operate the machine. The operating components are arranged within the structure in such a manner that the handle lies on a vertical line extending through the center of gravity of the entire machine.

ATTORNEY'S

BUTT END STITCHING MACHINE

BACKGROUND OF THE INVENTION

This invention concerns a sewing machine of the type usually called a butt end stitching machine and adapted to join fabric pieces end to end by means of a sewing operation performed on overlapped ends of the fabric pieces to be joined, associated with a fabric cutting-off operation performed parallelly and at a given distance from the seam, the seam allowing a subsequent coplanar arrangement of the joined fabric ends.

These types of machines are well known in the art. Owing to a special sewing operation to be performed, they comprise mechanisms widely different from those of usual sewing machines and the sewing operation is performed by means of a needle associated with a needle bar and cooperating with two hooks or "crochets" to which a suitably timed and synchronized reciprocating motion is imparted. The mechanisms further include a reciprocating blade shear and fabric feeding means in the form of a jaw and an opposite presser foot.

However, all known butt end stitching machines of this type are designed in such a manner as to operate in a stationary position, and to such a purpose they are always stationarily fitted on a worktable. Therefore, the fabrics to be sewn must be brought to the machine installation point and then set and guided concurrently with the fixed direction of the machine feeding devices. Such requirements result in considerable limitations to the machine operating capabilities and lead to not substantial difficulties, requiring skilled operators for conveying, positioning and guiding the fabric pieces. The above limitations and difficulties are considered as unavoidable in the art and also unavoidably associated with these machines.

As will be readily appreciated, the possibility to essentially avoid these normal operating conditions, i.e. to have a butt end stitching machine of the stated type that can be brought and operated where the fabric pieces to be joined are located, or at any rate that can be suitably moved, positioned and directed, would be highly desirable. Such hypothetical, desirable condition has never been considered as attainable in the art, due to conflicts thereof with mechanism assembling and operating requirements of the machines, even though it would result in obvious great advantages, e.g., similar to those offered by portable, electric sewing machines provided with a handle and typically utilized for sewing the openings of bags. At any rate, it appears that heretofore not even the possibility of solving the technical problems related to a machine of the considered type that can be gripped, conveyed and guided across the material to be sewn, was considered, seemingly due to the fact that the machine structure, mechanisms and technical solutions inherent to sewing and cutting operations are sharply conflicting with such a possibility.

SUMMARY OF THE INVENTION

An object of this invention is to solve the above technical problems and consequently to provide a portable and hand operable butt end stitching machine that can be gripped and guided by an operator in order to operate the same independently from any stationary supporting means thereof and which may be suitably positioned, directed and moved across fabric pieces to be joined.

The solution of above technical problems essentially involves adapting the machine structure to the desired new operating conditions, comprising machine gripping, supporting and guiding operations performed by an operator, as well as providing a suitable mass distribution to locate the center of gravity of the machine on a vertical line extending through the machine supporting point or points, and suitably designing connection mechanisms between driving means (in particular a high speed motor adapted to ensure a favorable power/weight ratio) and different fabric sewing, feeding and cutting devices.

The solution of the above and further technical problems will be disclosed in the following detailed description of an embodiment of this invention.

BRIEF DESCRIPTION OF THE DRAWINGS

FIG. 1 is a side view of a machine according to this invention, partially sectioned along different longitudinal planes to show the main components and mechanisms thereof.

FIG. 2 is a front view of the same machine, partially cross-sectioned along the plane II-II of FIG. 1.

DETAILED DESCRIPTION OF THE INVENTION

As shown, the butt end stitching machine comprises a structure mainly consisting of a suitably shaped hollow body 10, advantageously made of a light metal or alloy to decrease the machine weight and comprising a middle section 12, a lower fore section 14, having a top surface 16 defining a fabric feeding plane (between a feeding jaw 18 and a presser foot 20), and a suitably slanting upper fore section 22, wherein a needle bar 24 is slidably fitted. Body 10 is therefore approximately C-shaped when viewed sidewise. Under central section 12 the body has a gun like handle 26 adapted to be gripped by a machine operator. Handle 26 has a recess in the lower end thereof, wherein connection means 28 for an electric motor feeding flexible cable are located. The motor can be started and stopped by means of a suitable switch (not shown) that may be operated, e.g., by a trigger 30 or other suitable means.

The machine must be gripped, conveyed and operated without undue effort on the part of the operator, and such features require the solution of specific technical problems related to a suitable mass distribution of the machine and consequently to the design of various mechanisms thereof in order to obtain a machine having a reduced overall size and weight, suitably balanced with respect to gun handle 26. The handle should lie essentially along a vertical line containing the center of gravity of the whole machine, when ready to operate.

To achieve such purpose, a casing 34 housing a rather heavy electric motor (not shown) is fastened to a rear head 32 of body 10. Advantageously casing 34 supports a spindle 36 wherein a thread feeding spool may be fitted. The fore end 38 (FIG. 1) of a motor shaft, running at a high speed, carries an input pinion of a reduction gear unit 40 adapted to carry-out a required angular speed reduction. A machine main shaft 44 is driven by an outlet gear 42 of reduction unit 40. Reduction gear unit 40 is housed within a casing 46 adjacent to rearhead 32 and assists in balancing the machine by means of the weight thereof acting well rearwardly with respect to the handle 26. Moreover, an efficient lubrication of the reduction gear unit is ensured by casing 46, independently from that of all other

mechanisms unavoidably and at least partly exposed to the outside.

As is well known, a butt end stitching machine requires a needle bar 24 and means to operate a feeding jaw 18, as well as at least two hooks (not shown) reciprocally driven along a circular path about axes as defined by pins 48 and 50. Further, a cutter 52 reciprocally driven in a vertical plane is provided, together with the above mechanisms, within the machine fore sections 14 and 22. In order to suitably backwardly shift the center of gravity of the machine such operating components have driving means therefor embodying technical solutions widely different from conventional ones.

In particular, needle bar 24 is connected by a short connecting rod 54 with a long lever 56 pivotably fitted on an inclined pin 58. One arm 60 of lever 56 is connected by a ball joint 62 with a connecting rod 64, the other end 66 thereof cooperating with an eccentric keyed on main shaft 44 at a point close to gearbox 46. A short, crosswise extending shaft 70, whereon two eccentrics 72 are keyed, is driven by the same main shaft 44 through two gears 68. Eccentrics 72 control hook pins 48 and 50 through relatively long connecting rods 74,76 and levers 78,80, respectively. Shaft 44 further controls an eccentric 82 adapted to impart a reciprocating motion to an element 88, carrying cutter 52, through a connecting rod 84 and a second lever 86. Shaft 44 extends then forwardly to control a cam and eccentric assembly 90 that operates a support 92 of jaw 18.

Thus, these mechanisms (or other equivalent ones) reliably perform the different cutting and sewing operations and ensure a balancing of the mass of the machine with respect to gun handle 26 within the machine longitudinal plane (i.e. the plane of FIG. 1) by means of the structure and component distribution thereof. These conditions are necessary but not sufficient for a complete balancing of the mass of the machine in tridimensional space, and therefore this invention further comprises the solution of technical problems related to attainment of equilibrium conditions also in a plane extending crosswise through the center of gravity.

Such solution may be attained, e.g., by a mass and device distribution as shown in FIG. 2. The top portion of central section 12, wherein lever 56 and pin 58 are housed, is slanted in a direction opposite to the machine side wherein fabrics to be joined are fed in a direction A, on the working plane 16 and by means of feeding jaw 18. This mass distribution ensures an easy fabric feeding operation and engagement between jaw and presser foot 20. The weight of the devices that drive the lower sewing members is balanced by the weight of the elements in the slanting section 12 in such a manner that the machine center of gravity essentially lies in a vertical plane through the axis of main shaft 44. The motor 34 is co-axial with main shaft 44 and the gun handle 26 is fastened to body 10 in a laterally shifted position with respect thereto and essentially in the vertical plane through shaft 44. Presser foot 20 is in turn vertically adjustable by means of a double lever system 94 and 96 forwardly cantilevered with respect to the a fabric engagement point.

Obviously, structural solutions different from those described and shown may be carried-out, provided that an equivalence of drive means and stationary and movable mass distribution with respect to the gun handle is

maintained. Moreover, the entire weight of the machine need not necessarily be supported through the handle and the hand of the operator, since a shoulder strap system or even a movably supported extensible tie rod may be provided. At any rate, such strap or tie-rod means must not affect the machine guiding, directing and positioning features with respect to worked fabrics by means of the gun handle.

I claim:

1. A portable, hand-operated and hand-held butt end stitching machine of the type wherein fabric pieces may be joined end-to-end by first stitching together with loose butt end chain stitches two overlapped ends of fabric pieces while simultaneously cutting the overlapped ends along a line parallel to the line of stitching, and then rotating one of the fabric pieces about the cut line to arrange the fabric pieces coplanar and end-to-end, said machine comprising:

an elongated housing structure having at a first end thereof a horizontal planar fabric feeding surface, said housing structure extending in a direction orthogonal to the direction of fabric feeding;

a drive motor attached to a second end of said housing structure and having a drive shaft extending from said motor longitudinally into said housing structure;

a main shaft having a first end operatively connected to said motor drive shaft, said main shaft extending longitudinally through said housing structure and having a second end positioned adjacent said first end of said housing structure;

needle bar means having a needle mounted above said fabric feeding surface adjacent said first end of said housing structure;

first eccentric and lever means interconnected between said needle bar means and said main shaft for reciprocating said needle toward and away from said fabric feeding surface;

first and second hook means mounted below said fabric feeding surface adjacent said first end of said housing structure;

second eccentric and lever means interconnected between said main shaft and said first and second hook means for reciprocating said first and second hook means beneath said fabric feeding surface; a cutting means mounted adjacent said fabric feeding surface;

third eccentric and lever means interconnected between said cutter means and said main shaft for reciprocating said cutter means upwardly and downwardly;

there thus being a center of gravity of said machine located approximately midway of the longitudinal length thereof, said center of gravity being laterally offset to one side of said housing structure from a vertical plane longitudinally extending through and equally dividing said housing structure;

a gun-type handle attached to the bottom of said housing structure on a vertical line passing through said center of gravity;

said drive motor, said main shaft, and said handle being offset to said one side of said housing structure;

said first and second hook means, said second eccentric and lever means, said cutting means, and said third eccentric and lever means being offset and

positioned in the lateral side of said housing structure opposite said one side thereof; and said needle bar means and said first eccentric and lever means are slanted upwardly from a position

above and adjacent said opposite lateral side of said housing structure to a position above and spaced from said one side of said housing structure.
